CLAIM

I claim the ornamental design for a fume booster device, as shown and described.

DESCRIPTION

FIG. 1 is a rear view of a fume booster device;
FIG. 2 is a top view of the fume booster device;
FIG. 3 is a front view of the fume booster device;
FIG. 4 is a left side view of the fume booster device;
FIG. 5 is a right side view of the fume booster device;
FIG. 6 is a front perspective view of the fume booster device; and,
FIG. 7 is a rear perspective view of the fume booster device.
